UNITED STATES PATENT OFFICE.

EDWARD A. JOHNSON, OF ENID, OKLAHOMA.

SHEARS.

1,124,025.

Specification of Letters Patent.

Patented Jan. 5, 1915.

Application filed March 12, 1914. Serial No. 824,202.

To all whom it may concern:

Be it known that I, EDWARD A. JOHNSON, a citizen of the United States, residing at Enid, in the county of Garfield and State of Oklahoma, have invented certain new and useful Improvements in Shears, of which the following is a specification.

My invention relates to new and useful improvements in cutting shears, and as its 10 principal object aims to provide a pair of shears, the cutting blades of which consist of sleeve members which are slidably mounted on pivoted jaws and are adjustable, whereby they may be employed in the manner of ordinary cutting shears or may be quickly converted to perform the offices of button-hole scissors.

A further object is to provide in connection with the sliding sleeve blades a graduated scale upon which may be read the distance inwardly from the edge of the cloth or garment at which the button hole will be cut.

An object of equal importance with the foregoing is to construct the shears of this 25 invention with such regard to number, proportion and arrangement of parts that they may be cheaply manufactured, will be durable and efficient in their action, and may be easily and quickly converted to serve either 30 as ordinary cutting shears or as button-hole scissors.

The above and additional objects are accomplished by such means as are illustrated in the accompanying drawings described in 35 the following specification, and then more particularly pointed out in the claims which are appended hereto and form a part of this application.

With reference to the drawings, wherein 40 there has been illustrated the preferred embodiment of this invention as it is reduced to practice, and throughout the several views of which similar reference numerals designate corresponding parts,

45 Figure 1 is a perspective view showing my invention with the blades in open position; Fig. 2 is a side elevation, showing the blades in open position. In this figure the elevation is taken from the opposite side of the scis- 50 sors from Fig. 1; Fig. 3 is a section on the line 3—3 of Fig. 1; Fig. 4 is a longitudinal section taken through the blades with these members in closed position; Fig. 5 is a detail perspective view of one of the removable

sleeve blades; and Fig. 6 is a detail perspective view of the blade receiving arms of the scissors in open position.

The shears embodying my invention include a pair of blade receiving arms 10 and 11, which are enlarged at one end to produce 60 the terminal plates 12 and 13, respectively. These members 12 and 13 are pivotally united by an ordinary screw or similar element, indicated at 14.

Handles of the well known type are 65 formed on the terminal plates 12 and 13, as indicated at 15 and 16, respectively.

The blade receiving arms 10 and 11 are, as best shown in Fig. 6, reduced in width and in thickness toward their free terminals, 70 producing the three sections A, B and C. It will be seen that the sections A of the arms 10 and 11 are of less width and thickness than the plates 12 and 13, and that their outer faces are spaced from the outer faces 75 of the members 12 and 13, while their inner faces are spaced from the inner faces of these members, producing in the latter instance the shoulders indicated at 17 in Fig. 6. The shoulders 17 are in width equal to 80 the thickness of the inner walls of the cutting blades, as will be hereinafter fully disclosed.

It will now be noted that inasmuch as the section B is of less thickness than the 85 section A, and the section C is of less thickness than the section B, there are formed at the junction of these sections the shoulders 18 and 18'. It will further be seen that inasmuch as the section B is of less width than 90 the section A, and the section C is of less width than the section B, there will be formed at the junction of the longitudinal edges of the sections the shoulders 18² and 18³. These various shoulders are formed on 95 the arms 10 and 11 in order to abut similarly formed internal shoulders of the cutting blades so that the blades will be limited in their sliding movement on the receiving arms, and may be properly positioned 100 thereon.

These cutting blades, individually designated in Figs. 1 and 2 by the numerals 19 and 20, are formed of tempered sheet metal, although they may, of course, be cast if this 105 method be found more desirable and cheaper. As stated, these blade members 19 and 20 are formed in the nature of sleeves,

each including, as best illustrated in Fig. 5, side walls 21 and 22 and a cover flange 23. The side walls 21 and 22 are tapered or reduced in width toward their forward ends 5 so that the channels defined by the side walls 21 and 22 and top flange 23 are restricted toward the forward terminals of the blades, whereby the sleeves may be snugly fitted on the blade receiving arms 10 and 11, as shown 10 in Fig. 3 particularly.

It will be noted upon reference to Fig. 5 that the channels which are formed in each of the blade members are so reduced toward the forward terminals of the blades that they 15 form three chambers D, E and F. It will also be seen that the chamber E is less in width than the chamber D, while the chamber F is of less width than the chamber E. There are thus produced three chambers, 20 each corresponding in outline to the shape of the sections A, B and C of the blade receiving arms. It will be noted now upon reference particularly to Figs. 1 and 2 that the shoulders 18, 18', 18² and 18³ all abut 25 corresponding shoulders which are formed at the junctions of the three chambers D, E and F, which are defined by the side walls 21 and 22 and top flange 33 of the blades.

The lower edge of the side wall 21 is 30 slightly beveled, as indicated at 24, so that a sharp cutting edge 25 will be formed at the junction of the members 21 and 22. It may be well to explain at this point that the sleeve members or cutting blades 19 and 35 20 are formed of relatively resilient material so that, when placed on the arms 10 and 11, they will grip these members, being thus held against wabbling or shifting during the manipulation of the scissors.

40 As a means for holding the sleeves 19 and 20 in position on the arm members 10 and 11, the wall 21 of each sleeve member carries a rearwardly extending attaching plate 26 which is substantially rectangular in shape, 45 and is formed at the upper edge portion of the member 21, as best shown in Fig. 5. This member 26 is longitudinally slotted, as indicated at 27, so that it may receive a set-screw 28 which is threaded in the member 50 12 or 13, as the case may be. The flange 23 extends along the upper edge of the member 26, and engages the upper edge of the terminal plates 12 or 13, depending, of course, upon which arm receives the particular cutting blade.

When the shears are to be used as ordinary cutting shears, the cutting sleeves 19 and 20 are positioned on the arms 10 and 11 so that the rear edges 30 and 31 of the 55 inner walls 21 of the two sleeves 19 and 20 engage against the shoulders 17. The set-screws 28 are then threaded into the members 12 and 13 to firmly bind or clamp the attaching plate 24 thereagainst. The cutting sleeves or blades being thus held in

position on the pivoted arms 10 and 11, the operator may use the shears in the usual manner by grasping the handles 15 and 16.

Should it be desired, however, to quickly convert the shears into button-hole scissors, 70 it is only necessary to slide the sleeves forwardly on the arms 10 and 11 so that the rear edges 30 and 31 of the sleeves will be spaced from the shoulders 17 of the arms 10 and 11. When the blades are thus positioned, as shown in Figs. 1 and 2, it will be readily seen that the rear points or corners 75 32 and 33 of the blades may be efficiently employed in cutting button-holes.

It is, of course, desirable to provide means 80 whereby the length of the button-hole cut may be pre-determined. For this purpose, therefore, there is threaded into the upper edge of the member 13 a stop screw 34 which is adapted to engage with the hook-shaped 85 projection or stop 35 formed on the upper edge of the member 12, as best shown in Fig. 1. It will be seen that this member 34 may be threaded into or out of the member 13 to vary the length of the cut which may 90 be made by the rear edges or corners 32 and 33 of the blade.

As a means for enabling the operator to determine the distance from the edge of the cloth or garment at which the button-hole 95 will be cut, the lower edge of each attaching plate 26 is provided with a graduated scale which, when read in connection with the arrows embossed or otherwise formed on the members 12 and 13, as indicated at 36, 100 100 indicate the distance which separates the rear edges 30 and 31 of the blades from the shoulders 17. Inasmuch as the operator will pass the edge of the garment in between the blades until the edge engages with the shoulders 17, it is obvious that the distance of the proposed button-hole from the edge of the cloth or garment may be readily ascertained by means of the graduations on the members 26. 110

From the foregoing description, it will be noted that I have provided a pair of scissors which may be quickly and easily converted into button-hole scissors, and further that a new and sharp pair of cutting blades 115 may be substituted for worn-out blades by merely removing the screws 34. In this manner, the user of the shears may always have a sharp instrument, and may send the dull or worn-out blades to be re-sharpened 120 in the same manner as do users of safety razors.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the 130

fact that various minor changes in details of construction, proportion and arrangement of parts may be resorted to, when required, without sacrificing any of the advantages 5 of this invention, as defined in the appended claims.

What I claim is:—

1. A cutting instrument of the class described including a pair of pivotally united arms, a pair of cutting blades removably mounted on the arms, each of said cutting blades consisting in a sleeve which is adapted to slidably receive an arm, whereby the sleeves may be adjusted longitudinally on 10 the arms, and means for holding the sleeves in adjusted position.

2. In a cutting instrument of the class described, a pair of pivotally united arm members, and a removable cutting blade carried 20 by each of the arm members, each of said cutting blades consisting of a metallic sleeve member having side walls adapted to engage against the opposite faces of the arms and a flange extending from one of the side 25 walls and adapted to engage against the outer edge of the arm, a slotted extension formed on one of the side walls, and a retaining member threaded into the pivoted portion of each of the arms and disposed in 30 the slot of the adjacent extension for holding the sleeves in adjusted position.

3. A convertible cutting instrument of the class described including a pair of pivotally united arms, a pair of cutting blades removably carried by the arms, each of said cutting blades being formed in the nature of a sleeve slidably receiving one of the arms, a slotted extension formed on each sleeve and extending rearwardly therefrom, 40 and fastening means threaded into the pivoted portions of the arms and disposed in the slots of the extensions for holding the cutting blades in adjusted position on the arms, the rear terminals of the cutting 45 blades being adapted to serve for cutting button-holes when the blades are slid forwardly on the arms.

4. In a cutting instrument of the character described, a pair of pivotally united arms, a removable cutting blade carried by 50 each of the arms, each of said cutting blades consisting of a sleeve having side walls adapted to engage against the opposite faces of an arm, and a flange extending from one 55 of the side walls and engageable against the outer edge of the arms, and means for adjustably securing the blades on the arms.

5. A convertible cutting implement of the character described including a pair of pivotally united arms, a pair of cutting blades removably carried by the arms, each of said cutting blades being formed in the nature of a sleeve slidably receiving one of the arms, a slotted extension formed on each sleeve and 65 extending rearwardly therefrom, and means

passing through the extension and engaged with the arms adjacent their pivoted portions for adjustably securing the blades in position.

6. A convertible instrument of the character described including a pair of pivotally united arms, a removable cutting blade carried by each of said arms, each of said cutting blades being formed in the nature of a sleeve and including a pair of side walls engageable against opposite faces of an arm, a flange extending from one side wall and engageable against the outer edge of each arm, a slotted extension formed on one side wall and engageable against the outer face of the arm, a fastening member passing through 70 the slot of the extension and engaging in the arm adjacent the pivotal point thereof for securing the blade in adjusted position upon the arm, and means for limiting the movement 75 of the arms whereby the rear terminals of the cutting blades may be employed for cutting button holes.

7. A convertible cutting implement of the character described including a pair of pivotally united arms, a hook-shaped stop member formed on one of the arms adjacent its pivotal point, an adjustable member carried by the other arm and engageable with the stop member for limiting the movement 90 of the arms, a pair of cutting blades removably mounted on the arms and adapted to be adjusted longitudinally thereon, and means for holding the cutting blades in adjusted 95 position whereby the rear terminal portions 100 of the cutting blades may be secured in different positions for cutting button holes of different lengths.

8. A cutting implement of the character described including a pair of pivotally united arms, terminal plates formed on the arms to receive the pivotal connection thereof, said plates having their forward edges arranged at approximate right angles to the arms providing lateral shoulders, a pair of cutting blades removably mounted on the arms, each of said blades being formed in the nature of a sleeve, the terminals of the blades being engageable against said shoulders when the blades are in normal position 105 on the arms, and means for adjustably securing the blades on the arms whereby the rear terminals of the blades may be moved forwardly and spaced from the shoulders to adapt the rear terminals of the blades for 110 use in cutting button holes.

9. A cutting instrument of the character described including a pair of pivotally united arms, each of said arms having a plurality of spaced transversely extending shoulders formed on its outer face, a blade member slidably mounted on each of said arms, each of said blade members being formed in the nature of a sleeve and having longitudinally spaced transversely extend- 115 120 125 130

ing internal shoulders, the shoulders of the sleeves being engageable against the shoulders of the arms when the sleeves are in normal position thereon, and means for adjustably securing the blades in position on the arms.

In testimony whereof I affix my signature in presence of two witnesses.

EDWARD A. JOHNSON.
